(57) **CLAIM**

The ornamental design for a remote controller for automobile alarm system, as shown and described.

DESCRIPTION

FIG. 1 is a perspective view illustrating our new design for a remote controller for automobile alarm system;
FIG. 2 is a front elevational view of the remote controller for automobile alarm system of FIG. 1;
FIG. 3 is a rear elevational view of the remote controller for automobile alarm system of FIG. 1;
FIG. 4 is a top plan view of the remote controller for automobile alarm system of FIG. 1;
FIG. 5 is a bottom plan view of the remote controller for automobile alarm system of FIG. 1;
FIG. 6 is a right side elevational view of the remote controller for automobile alarm system of FIG. 1; and,
FIG. 7 is a left side elevational view of the remote controller for automobile alarm system of FIG. 1.
